SINGLE WHEEL TOTE CART FOR
GARBAGE CANS

Stanley R. Massoll, 25306 Donald, Detroit, Mich.

Filed Sept. 29, 1964, Ser. No. 81,917

Term of patent 7 years

(Cl. D14—3)

FIG. 1 is a side elevational view of a single wheel tote cart for garbage cans, embodying my new design.

FIG. 2 is a front elevational view thereof.

FIG. 3 is a top plan view thereof.

I claim:

The ornamental design for a single wheel tote cart for garbage cans, as shown.
